UNITED STATES PATENT OFFICE.

CHARLES L. DAHLBERG, OF DES MOINES, IOWA.

BOOK-SUPPORT.

1,278,442.

Specification of Letters Patent. Patented Sept. 10, 1918.

Application filed August 20, 1917. Serial No. 187,242.

To all whom it may concern:

Be it known that I, CHARLES L. DAHLBERG, a citizen of the United States, and resident of Des Moines, in the county of Polk and State of Iowa, have invented a certain new and useful Book-Support, of which the following is a specification.

My invention relates to book supports for holding an open volume for reading or 10 copying therefrom.

The object of my invention is to provide such a book support having movable members connected with each other in such manner that they may be readily adjusted for 15 holding a book resting thereon, in proper position for reading or copying from the book, regardless of the point at which the book may be open.

Still a further object is to provide such a 20 device having means for holding the pages flat when the book is open, which means is adjustable for fitting books of different sizes.

With these and other objects in view, my 25 invention consists in the construction, arrangement and combination of the various parts of the device, whereby the objects contemplated are attained, as hereinafter more fully set forth, pointed out in my claim, and illustrated in the accompanying 30 drawings, in which:

Figure 1 shows a perspective view of a book support embodying my invention.

Fig. 2 shows a side elevation of the same.

Fig. 3 shows an enlarged, detail view of 35 the means for connecting the two slidable members.

Fig. 4 shows a detail, sectional view, taken on the line 4—4 of Fig. 3.

Fig. 5 shows a vertical, sectional view, 40 taken through the central portion of the leaf holding weight or bar, and

Fig. 6 shows a detail, sectional view of the mechanism for holding the adjustable leaf holding bar.

45 In the accompanying drawings I have used the reference numeral 10 to indicate generally a base which may be made of any suitable material, such, for instance, as a wooden board. Arranged on the upper surface of the base 10, in the center thereof, and 50 extending from front to rear of said base, is a strip 11. At each end of the base 10 is a metal plate or strip 12, which extends upwardly beyond the base 10, as shown in

Fig. 1. On each side of the strip 11 is a 55 slidable member 13, which may comprise a board. The members 13 slide fore and aft in the device between the strip 11 and the respective strips 12 which form guideways.

Hinged to the forward end of each slidable member 13 is a book supporting member 14. The members 14 are designed in one position to rest immediately above the slidable members 13 so as to occupy a minimum of space. When in actual use for holding a 60 book, the members 14 incline from their lower forward edges upwardly and rearwardly, as illustrated in Fig. 1.

Pivoted to the rear surface of each book supporting member 14 is a supporting base 70 15, having at its lower end a portion or member 16 adapted to rest on the proper slidable member 13 and to be extended under a hook device 17 on the upper surface of the member 13. The hook device prevents 75 the brace from sliding rearwardly, and holds the book supporting member 14 in proper raised position.

In a book support of this kind, it will be understood that the left hand member 14 80 supports the front cover of the book, while the other member 14 supports the rear cover thereof. When the book is open at its middle, it is desirable that the members 14 should be in alinement from side to side. 85 When, however, the pages of the book are turned so that the portion of the book at one side of the center thereof is considerably thicker than the portion at the other side of said center, then it is desirable that the member 14 which supports the thicker portion of the book should be slightly rearwardly of the other member 14. In other words, it is desirable that the members 14 should be capable of fore and aft sliding movement in the machine with respect to each other, and it is also desirable that the movement of one of said members 14 should correspond with the other of said members for properly supporting the book. It thus appears that 90 where the members 14 are adjustable in the manner just mentioned, they can easily be so adjusted that the open pages of the book may be substantially in the same plane.

For properly connecting the members 14, or rather the members 13 which carry the members 14, the following means has been provided. Centrally pivoted on the upper

surface of the strip 11, preferably approximately near the center thereof from front to rear, is a flat bar 18 preferably made of metal or the like, and having its ends adapted to extend over and to overlap the upper surfaces of the members 13 when the bar 18 is in transverse position in the device, as illustrated in Figs. 1 and 3. Near each end of the bar 18 is a longitudinally elongated slot 19. On the upper surface of each of the slideable members 13 is an upwardly extending lug or pin 20, the upper end of which projects into one of the slots 19.

By the mechanism just described, it will be seen that when either one of the members 14 is pushed rearwardly or forwardly in the device, the other of the members 14 will be caused to travel correspondingly forwardly or rearwardly.

20 In Fig. 1 I have shown the members 13 and 14 in position for receiving a book open approximately at its middle, while in Fig. 2, in dotted lines, I have shown the members 14 in different positions fore and aft of the device and in position for holding a book where a considerably larger portion of the book rests on one of the book supports than on the other book support.

For holding the leaves of the book open, 30 and also for use in reading line by line or the like, I have provided the following means. Mounted on the upper surface of the strip 11, at the forward end thereof, is a downwardly opening U-shaped bracket 21 having 35 spaced arms which are provided with opposite pairs of holes 22 so arranged that the openings 22 of one arm of the bracket register with the openings 22 in the other arm thereof. The arms of the bracket 21 at their 40 lower ends have laterally extending flanges 23 which are secured to the strip 11 by means of screws or the like 24. At the upper end of the bracket 21 said bracket is provided at its rearward edge with a notch 45 25. I provide a rod 26, the lower end of which is flattened to fit between the arms of the bracket 21. The flattened end of the rod 26 is provided with a plurality of holes 27 such as those indicated by dotted lines 50 in Fig. 6. The lower end of the rod 26 is pivotally connected with the bracket 21 by means of the pin 28 selectively extended through an opposite pair of openings 22 and one of the openings 27. The openings 22 are 55 located near the rear edges of the bracket 21, and the notch 25 is of such depth that when the rod 26 is swung upwardly the lower flattened portion of the rod 26 will be received in the notch 25 for permitting 60 the rod 26 to swing a trifle past vertical, so that when the rod 26 is swung upwardly and forwardly in the device to position where it is received in the notch 25, said rod 26 will remain in its raised position until moved 65 forwardly.

I provide a weight bar 29 which is provided with an opening at its central portion, whereby said weight bar is slidably and rotatably mounted on the rod 26. The weight bar 29 may be locked on the rod 26 in a variety of positions by means of a set screw 30. 70

In the practical use of my improved book support, the rod 26 is raised to position shown in full lines in Fig. 1, and the book is placed open on the book supports 14, as 75 illustrated by dotted lines in said figure. If the book is opened approximately at its middle, the members 13 and 14 are left practically in alinement with each other from side to side in the device. If, however, the book is opened near the front or back or at any point aside from the center, that book supporting member 14 which supports the larger part of the book is moved slightly rearwardly with relation to the other book support, until the exposed open pages of the book are substantially in the same plane. The weight bar 29 is then swung forwardly until it rests upon the open pages of the book, as shown in dotted lines in Fig. 1. 80 The rod 26 may be adjusted to a variety of positions for use with different sizes of books, by the selective mounting of the pin 28 in different holes 22 and 27. The weight bar 29 may be quickly and easily adjusted 85 on the rod 26, so as to cause it to rest in any desired position on the book. 90

It will be seen that when the book is placed on the members 14, a very easy adjustment may be had by pushing on either side of the book or upon either of the members 14 or 13, and that the movement of one member 13 or 14 causes a corresponding opposite movement of the other member 13 or 14. It should be noted that the sliding members 13 are normally held by friction against 95 sliding movement. 100

In many offices, such for instance as those of makers of abstracts of title and the like, it is desirable to have a quickly operated and accurate line guide. It will be seen that the bar 29 may be quickly and easily adjusted on the rod 26, so that it affords such 110 a line guide. 105

When the device is not in use, the brackets 15 may be swung forwardly against the under surfaces of the members 14, and the members 14 may then be collapsed downwardly and rearwardly until they rest just above the members 13. The rod 26 and bar 29 may then be lowered rearwardly, so that the collapsed device occupies a minimum space for storage or transportation. 115 120

Some changes may be made in the construction and arrangement of the parts of my improved device, without departing from the essential features and purposes thereof, and it is my intention to cover by the claim which may be allowed upon my application, 125 any modified forms of structure or use of 130

mechanical equivalents which may be reasonably included within the scope of my claim.

I claim as my invention:

A book support comprising a base, a pair of members mounted to slide horizontally thereon and to be normally held by friction against slidable movement, a book support-

ing member mounted on each of said slidable members and an equalizer interposed between said slidable members and operatively connected therewith and with said base. 10

Des Moines, Iowa, July 31, 1917.

CHARLES L. DAHLBERG.
